MANUFACTURE OF SOAP

Ashton T. Scott, Bryn Mawr, Pa., assignor to The Sharples Corporation, Philadelphia, Pa., a corporation of Delaware

Application February 26, 1942, Serial No. 432,375

10 Claims. (Cl. 260—418)

The present invention relates to the art of soap-making, and this application is a continuation in part of my co-pending application, Serial No. 333,547, filed May 6, 1940, now Patent 2,300,749, November 3, 1942. My prior application pertains to a continuous process for manufacture of soap by continuously mixing a saponifying reagent with a source of fat to effect saponification thereof, and separating soap formed by the saponification reaction from spent saponifying reagent by centrifugation. The present application pertains to the special procedure described on pages 12 and 13 of that prior application, by which the soap formed in the continuous soap-making operation is discharged from the centrifugal rotor and passed to the zone of subsequent treatment or use under the influence of its own rotational inertia.

As pointed out in my prior application referred to above, the problem of removal of the soap from the centrifugal in which it is separated from the aqueous phase presents very considerable difficulty in connection with the continuous manufacture of soap with the aid of centrifugal separators. This problem becomes greater as the thoroughness of the graining operation by which the soap is precipitated and washed from the spent lye is improved. In accordance with the principal embodiment of the invention of my prior application, the soap and aqueous phases are discharged from the respective centrifugals under liquid balance over weirs, and the soap is discharged from the centrifugal covers into which it is discharged over the weirs with the aid of an aqueous liquid which is separately introduced into the covers. By the present invention the soap may be discharged from the centrifugal even in cases in which it is too hard and granular to be discharged over a weir.

It is a well-known fact in the art of soap manufacture that soaps formed from certain fats form harder grains than others. These harder-grained soaps are difficult, and sometimes impossible, to discharge over a weir of a centrifugal separator, and a feature of the invention consists in the fact that it renders the process of continuous centrifugal soap-making feasible, even with fats which form grains of unusual hardness.

In accordance with the present invention, instead of discharging the soap into a centrifugal cover across a weir, it is discharged from the centrifugal, and may be passed from the centrifugal into a conduit leading to the following mixer, under its own rotational inertia. To ac-

complish this end in accordance with the present invention, a stationary skimming nozzle or similar dislodging tool is positioned within the centrifugal rotor at a point substantially tangential to the path of rotation of the soap in that rotor under the influence of centrifugal force, with the result that the kinetic energy of the soap caused by its movement around the axis of the centrifugal rotor is largely converted into pressure within a pipe connected to the skimming nozzle, and the soap is accordingly removed from the centrifugal rotor under the influence of its own inertia.

Further features of the invention and the manner in which they have been attained will be evident from a reading of the following detailed description in the light of the attached drawings, in which

Figure 1 is a flow sheet illustrating the fundamental steps in the practice of the invention,

Figure 2 is a central longitudinal cross section through a centrifugal separator used in the practice of the invention, and

Figure 3 is a cross section on the line 3—3 of Figure 2.

In the practice of the invention as illustrated in Figure 1 of the drawings, a saponifiable mass, such as neutral fat from container 10, is passed by pump 11 to a mixer 12, where it is mixed with a saponifying reagent passed from container 14 by pump 15 into confluence with the source of fat in this mixer.

The mixer 14 may be any suitable type of mixer adapted to effect violent mixing of the saponifying reagent with the source of fat, but a multi-stage high-speed mechanical mixer is preferred for performance of the mixing function. The mixing of the saponifying reagent with the fat at a saponifying temperature results in formation of soap, and the soap-containing mass is mixed with a salting-out agent, such as a salt solution from container 16 in order to condition the soap for subsequent centrifugal separation from aqueous phase. While the salt solution is indicated on the flow sheet as being added at an advanced stage of the mixer, it may be added at any suitable point, and there are certain very definite advantages in adding it at an earlier stage, either separately, or as a part of the solution of saponifying reagent, as taught in my co-pending application Serial No. 334,297, filed May 10, 1940, for Manufacture of soap, now Patent 2,300,750, November 3, 1942. In connection with these features of the invention, it includes saponifying and salting-out steps, regardless of whether the

salting-out step is performed subsequent to complete formation of soap in the mixer, at an intermediate stage of soap formation, or at the time the soap is formed by introduction of the salting-out agent simultaneously with the saponifying reagent. The present invention is not limited to any particular sequence in this connection, or to the use of any particular salting-out or graining agents. It is only necessary, in this stage of the reaction, that a saponifying reagent be added to effect saponification of a substantial proportion of the fat, and that the soap resulting from this reaction be grained or precipitated from solution by the presence of a suitable agent for effecting that end; this graining or precipitating agent may, for example, be a suitable electrolyte. As an example of the possibilities of graining within the broad scope of the invention, it may be pointed out that the graining operation may be accomplished by addition to the reaction mixture of an amount of the saponifying reagent in excess of that required to react with the fat under treatment in manufacture of soap.

The violent agitation of the soap-containing mass is preferably continued during the progress of this material practically up to the instant when this material enters the centrifugal separator 18. By continuing the agitation in this manner, the mass is maintained in a condition of substantially uniform dispersion of the grained soap within the aqueous phase, with the result that continuous and fairly uniform feed to the centrifugal separator 18 occurs. The centrifugal separator 18 may be of any type suitable for discharge of the soap substantially tangentially from the centrifugal under its own rotational inertia while separating and separately discharging the aqueous phase. I prefer to use a centrifugal of the type illustrated in the patent to Jones 2,089,123, and in Figures 2 and 3 of the present drawings.

Referring to Figure 2 of the drawings, the numeral 30 designates a centrifugal rotor. The mixture of the grained soap with aqueous phase leaving the mixer 12 is fed to the centrifugal rotor by means of a feed nozzle 31 communicating with a central tube 32 constituting a part of the centrifugal rotor. The mixture to be centrifuged passes from the central tube 32 into the main body of the rotor through radially extending passages 33. The rotor contains a plurality of stratifying plates 34 adapted to facilitate centrifugal separation of constituents of the mixture, these stratifying plates being in the form of nested frusto-conical discs in the form of the invention illustrated.

It is to be noted that the discharge passages 33 deliver the mixture to be subjected to centrifugation to a zone of the rotor within the inner termini of the stratifying plates 34. The purpose of delivering the mixture to this zone is to effect subsidence of a large part of the lighter and more viscous soap without passing such soap to the zone occupied by the stratifying plates. This feature minimizes coggage of the stratifying plates by the soap.

The rotor is provided with a frusto-conical dividing wall 35, and the heavier material sedimented as the outer stratum within the rotor is continuously discharged around the outer edge of this dividing wall and through passages 36 located between this dividing wall and the upper part 37 of the rotor. This aqueous phase is continuously discharged into the receiving cover 38 of the centrifugal. A dislodging tool in the form of a skimming nozzle 39 which is reciprocable toward and

away from the stratum of soap occupying the inner radial zone of the material stratified within the rotor is provided for discharge of this curdy material.

5 A consideration of the mode of operation of this machine in the separation of soap from aqueous phase after discharge from the mixer 12 will illustrate the nature of the present invention. In the separation of soap from the aqueous phase, the rotor is first set in rotation, and the mixture from the mixer 12 is fed to the main body of the rotor through the feed nozzle 31 and the central tube 32 with its radiating passages 33. As the mixture accumulates in the rotor, the heavier spent lye solution will be sedimented from the soap and flow outwardly, around the frusto-conical dividing wall 35 and through the passages 36 into the liquid receiving cover 38. The layer of soap, accumulating within the portion of the rotor lying inwardly of the inner termini of the discs 34, will be discharged through the skimming nozzle 39.

The rotor 30 preferably includes means 40 for maintaining the soap which occupies the portion of the rotor lying inwardly of the inner termini of the stratifying plates 34 at a speed of rotation substantially the same as the speed of the rotor. These means constitute, in the form of the invention illustrated, accelerator structure in the form of a plurality of radially extending webs or wings which may be formed integrally with the central tube 32 and extend radially from this central tube to the inner termini of the stratifying plates 34. These wings contain portions in the form of webs 41 extending a substantial distance longitudinally of the rotor and occupying the full depth of the inner soap stratum within the rotor. These webs, at their outer radial extremities, are preferably enlarged to form ribs 42, which also assist in maintaining the viscous soap at approximately the speed of bowl rotation, and which extend throughout substantially the entire longitudinal zone of the rotor occupied by the viscous soap. The zone of the rotor adjacent the skimming nozzle 39 is of course left free of accelerator structure in order to afford provision for unobstructed movement of the skimming nozzle. The upper ends of the ribs 42 are preferably connected together by means of an annular frusto-conical rigidifying disc 43. The outer radial extremities of the ribs 42 preferably abut the inner radial extremities of the stratifying plates 34 and tend to center these stratifying plates within the rotor. One of these ribs is preferably provided with a key 44, as illustrated, which enters into slots formed in the stratifying plates and thus insures the rotation of these plates at the same speed as the rotor.

As pointed out above, the soap accumulating as the inner stratum in the centrifugal rotor is continuously impelled, under energy derived from its own inertia of rotation, in a substantially tangential direction into the skimming nozzle 39 and the piping connected with that skimming nozzle through which it is passed to the next zone of treatment or use. As illustrated in the drawings, it is passed in this manner to the mixer 19 in the second stage of the soap-making process, where it may be mixed with water from container 23, and a further quantity of saponifying reagent from the container 20 in three separate increments to effect further saponification and graining. From this mixer, it is passed by pump 21 to a second centrifugal 22 which is identical with the centrifugal 18. Soap which is separated from

aqueous phase in this second centrifugal is discharged to the next zone of treatment or use with the aid of a skimming nozzle in the same manner as that employed in discharge of soap from the centrifugal 18, and aqueous phase separated similarly to the aqueous phase from centrifugal 18 may be returned by pump 24 to container 13, from which it is passed into confluence with further saponifiable material in the mixer 12 to assist in the primary saponification step. Soap discharged from centrifugal 22 may be mixed with water to effect the "fitting" operation, and the resulting mixture then subjected to centrifugation to separate nigre from neat soap in a centrifugal similar to centrifugals 18 and 22, the neat soap being discharged by a skimming nozzle, while the aqueous phase (nigre) is separately discharged.

While an embodiment of the invention has been illustrated in which soap discharged from the centrifugal 18 is passed from that centrifugal to the mixer 19 under impelling force derived from rotation in the centrifugal 18, it will be evident that a pump may be provided in the conduit connecting the centrifugal 18 with the mixer 19, if desired. In either case, an important advantage is attained in practice of the present invention by deriving the necessary force for discharging sedimented soap from the zone of centrifugation, from the soap itself, as that soap rotates in the centrifugal in which it is stratified.

A further advantage of the invention consists in the fact that it can be effectively used in connection with an operation including spraying the soap with an aqueous solution of an electrolyte, such as brine, during the centrifugal separation of the soap from aqueous phase. Thus, brine may be fed from container 16 through conduit 45 and sprayed through openings of tube 46 from this conduit onto the rotating body of soap in the centrifugal. By operating in this way, and using strong brine or other strong electrolyte solution as the washing and graining agent sprayed through the openings of the tube 46, it is possible to produce a very granular soap stratum, with the result that unusually efficient washing is obtained. In spite of the fact that the soap stratum is made quite granular by this operation, it is possible to discharge it under the effect of its own inertia through the skimming nozzle 39. Thus, by providing a process which renders discharge of a more granular soap from the centrifugal possible, thorough washing of the soap in the centrifugal is rendered feasible, with the result that the soap discharged from the centrifugal of the first stage is a much purer product than could otherwise be obtained.

Various modifications are possible within the scope of the invention, and I do not therefore wish to be limited except by the scope of the following claims.

I claim:

1. In the separation of grained soap from saponifying reagent solution, the process comprising passing the mixture of grained soap and saponifying reagent solution into the rotor of a centrifugal separator, causing sedimentation of saponifying reagent solution from the soap by rotation of the rotor, discharging saponifying reagent solution from said rotor, and separately discharging sedimented soap from said rotor substantially tangentially under the influence of its own rotational inertia by projection of said soap against a non-rotating dislodging tool main-

tained in the path of rotation of said sedimented soap within said rotor.

2. In the manufacture of soap, the continuous process comprising saponifying and graining a saponifiable material to form a mixture of soap and aqueous phases, passing the mixture of soap and aqueous phases into the rotor of a centrifugal separator, causing sedimentation of aqueous phase from the soap by rotation of the rotor, discharging aqueous phase from said rotor, and separately discharging sedimented soap in a substantially tangential direction from said rotor under the influence of its own rotational inertia by projection of said soap against a non-rotating dislodging tool maintained in the path of rotation of said sedimented soap within said rotor.

3. In the manufacture of soap, the continuous process comprising saponifying and graining a saponifiable material to form a mixture of soap and aqueous phases, passing the mixture of soap and aqueous phases into the rotor of a centrifugal separator, causing sedimentation of aqueous phase from the soap by rotation of the rotor, discharging aqueous phase from said rotor, and separately discharging sedimented soap from said rotor by maintaining a non-rotating dislodging tool in the path of the rotating body of sedimented soap in said centrifugal rotor and thereby propelling said soap from said rotor.

4. In the manufacture of soap, the continuous process comprising saponifying and graining a saponifiable material to form a mixture of soap and aqueous phases, passing the mixture of soap and aqueous phases into the rotor of a centrifugal separator, causing sedimentation of aqueous phase from the soap by rotation of the rotor, discharging aqueous phase from said rotor, and separately discharging sedimented soap from said rotor by maintaining a non-rotating skimming nozzle in the path of the rotating body of sedimented soap in said centrifugal rotor and thereby propelling said soap from said rotor.

5. In the manufacture of soap, the continuous process comprising saponifying and graining a saponifiable material to form a mixture of soap and aqueous phases, passing the mixture of soap and aqueous phases into the rotor of a centrifugal separator, causing sedimentation of aqueous phase from the soap by rotation of the rotor, discharging aqueous phase from said rotor, and separately discharging sedimented soap from said rotor and removing said separated sedimented soap from the centrifugal separator by maintaining a non-rotating skimming nozzle in the path of the rotating body of stratified soap in said centrifugal rotor and thereby propelling said soap through said skimming nozzle into a conduit by which it is removed from said centrifugal separator under force derived from its inertia of rotation in said rotor.

6. In the manufacture of soap, the continuous process comprising saponifying and graining a saponifiable material to form a mixture of soap and aqueous phases, passing the mixture of soap and aqueous phases into the rotor of a centrifugal separator, causing sedimentation of aqueous phase from the soap by rotation of the rotor, discharging aqueous phase from said rotor, separately discharging sedimented soap from said rotor and removing said separated sedimented soap from the centrifugal separator by maintaining a non-rotating skimming nozzle in the path of the rotating body of sedimented soap in said centrifugal rotor and thereby propelling said soap through said skimming nozzle into a

conduit by which it is removed from said centrifugal separator under force derived from its inertia of rotation in said rotor, and delivering said soap from said conduit into a mixer in which it is mixed with a further quantity of saponifying reagent in a further stage of the process.

7. In the manufacture of soap, the process comprising separating soap from aqueous phase by passing a mixture of soap and aqueous phase into the rotor of a centrifugal separator, causing sedimentation of aqueous phase from the soap by rotation of the rotor, washing the sedimented soap by introducing an electrolyte solution into the central portion of said rotor within the soap stratum formed by sedimentation of said soap, discharging aqueous phase from said rotor, and separately discharging sedimented soap from said rotor under the influence of its own rotational inertia by projection of said soap against a non-rotating dislodging tool maintained in the path of rotation of said sedimented soap within said rotor.

8. In the manufacture of soap, the continuous process comprising saponifying a saponifiable material, therewith graining the saponified mass to form a mixture of soap and aqueous phases, passing the mixture of soap and aqueous phases into the rotor of a centrifugal separator, causing sedimentation of aqueous phase from the soap by rotation of the rotor, discharging aqueous phase from said rotor, and separately discharging sedimented soap tangentially from said rotor under the influence of its own rotational inertia by projection of said soap against a non-rotating dislodging tool maintained in the path of rotation of said sedimented soap within said rotor. 35

9. In the manufacture of soap, the continuous process comprising saponifying and graining a saponifiable material by substantially simultaneous addition thereto of a saponifying reagent and a salt to form a mixture of soap and aqueous phases, passing the mixture of soap and aqueous phases into the rotor of a centrifugal separator, causing sedimentation of aqueous phase from the soap by rotation of the rotor, discharging aqueous phase from said rotor, and separately discharging sedimented soap substantially tangentially from said rotor under the influence of its own rotational inertia by projection of said soap against a non-rotating dislodging tool maintained in the path of rotation of said sedimented soap within said rotor.

10. In the manufacture of soap, the continuous process comprising saponifying and graining a saponifiable material by addition thereto of a sufficient molecular excess of a saponifying reagent to perform both saponifying and graining functions and to form a mixture of soap and aqueous phases, passing the mixture of soap and aqueous phases into the rotor of a centrifugal separator, causing sedimentation of aqueous phase from the soap by rotation of the rotor, discharging aqueous phase from said rotor, and separately discharging sedimented soap substantially tangentially from said rotor under the influence of its own rotational inertia by projection of said soap against a non-rotating dislodging tool maintained in the path of rotation of said sedimented soap within said rotor.
